JACOB Z. HUMBERT, OF NORTH CANTON, OHIO

LID STRAIGHTENING AND SEALING TOOL

Application filed September 1, 1931. Serial No. 560,647.

The invention relates to tools for straightening the sealing flange or lids for containers, and more particularly to a tool to be applied to a lid on a Mason jar for forcing the sealing flange of the lid into sealing engagement with the usual gasket to effect a perfect seal around the entire periphery of the lid.

The sealing flange on the ordinary Mason jar lid is extremely thin and flexible, and therefore easily distorted and bent out of shape. Thus it often happens in using new lids that a perfect seal is not effected between the lid and gasket unless great force is applied in screwing the lid on the jar, so as to force the flange down into the gasket sufficiently to seal the bent portions of the flange.

It is common practice, in removing the lids from Mason jars, to insert a knife or other sharp instrument between the sealing flange of the lid and the gasket to permit air to rush into the jar, when the lid may be usually removed with comparative ease. This practice usually results in bending or distorting the sealing flange of the lid so that it may not be used again without reshaping.

In the past, tools have been provided for reshaping the sealing flange of jar lids, said tools consisting of male and female dies between which dies the sealing flange is straightened. With such tools, however, the lid must be straightened or reshaped before being applied to the jar, and the tool cannot be used satisfactorily to aid in the actual sealing of the lid upon the jar, after the lid has been straightened on the dies.

It has been proposed to provide a tool to be applied to the jar lid in position upon the jar, the tool having means for applying a downward pressure upon the sealing flange for straightening the same. In such case the perfectness of the seal is dependent upon the efficiency of the straightening means, and in the event the flange is badly bent and has depressions therein, the straightening means does not satisfactorily straighten the flange because of the absence of a rigid forming die beneath the flange.

It is an object of the present invention to provide a straightening and sealing tool which may be applied to a jar lid in position

on the jar, said tool having means for crimping the edge of the sealing flange into the gasket around the entire periphery of the lid.

Another object is to provide a straightening and sealing tool which, in the case of 55 badly distorted lids, may be first applied to the lid positioned on a jar with a forming ring located under the sealing flange for straightening the flange, and then applied to the lid positioned on the jar with the usual 60 gasket to seal the lid thereon.

Another object is to provide a straightening and sealing tool which will simultaneously seal and straighten the sealing flange, and which is extremely simple and inexpensive to manufacture, requiring little or no skill and a minimum amount of exertion in applying it to a jar lid to effectively straighten and/or seal the same.

The above and other objects are accomplished by the parts, methods and combinations comprising the present invention, which may be stated in general terms as including a cup-shaped sealing tool adapted to rotatably fit around a jar lid, the lower edge of 70 the tool being adapted to ride upon the upper surface of the sealing flange, and the wall of the tool being provided with a depending tapered lug portion formed therein and adapted to extend below and wedgably engage over the outer edge of the sealing flange to crimp the same downwardly inward 75 into a rubber gasket or around a forming die when the tool is rotated on the lid.

A preferred embodiment of the present improvements is illustrated in the accompanying drawing in which

Figure 1 is a bottom plan view of the straightening and sealing tool;

Fig. 2 is a sectional view of the tool as on line 2-2, Fig. 1;

Fig. 3 is an elevation view of the tool in position around the lid on a Mason jar, the tool being shown in section;

Fig. 4 is a perspective view of the forming ring or die to be used in connection with badly bent lids; and

Fig. 5 is a view similar to Fig. 3 showing the straightening tool in position to form 100

the sealing flange around the forming ring which is positioned upon a jar.

Similar numerals refer to similar parts throughout the several views.

5 The improved straightening and sealing tool indicated generally at 10, is preferably cup-shaped, and includes the top wall 11 and the annular side wall 12. The outer surface of the side wall 12 may have a knurled portion 13 for facilitating rotation of the tool by hand. The bottom 14 of the side wall preferably has its inner edge bevelled as shown at 15.

15 At one location on its periphery the side wall 12 is preferably depressed or indented to form a groove 16 in its outer surface and a corresponding ridge 17 on its inner surface, the groove and ridge thus formed extending upwardly a substantial distance from the bottom 14 of the side wall 12. The bottom portion of the ridge 17 is formed into a lug portion 18 depending below the bottom 14 of the side wall, and the inner wall of the lug portion 18 preferably tapers inwardly upward, as shown at 19, into the surface of the ridge 17.

20 Although only one ridge 17 is illustrated in the drawing, it will be understood that a plurality of these ridges may be formed 30 without departing from the scope of my invention.

25 The inner diameter of the tool 10 is such that when placed over a Mason jar lid 20, the bevelled edge 15 of the tool rests upon and conforms to the contour of the upper surface of the outwardly flared sealing flange 21, and the depending lug 18 extends below the bottom edge of the sealing flange 21 with the tapered portion 19 frictionally engaging the sealing flange. In this position the inner surface of the side wall 12 contacts with one or more of the threads of the lid 20 at points preferably diametrically opposite the ridge 17, as shown at 22 in Fig. 3.

40 45 In the operation of the tool, a jar lid 20 is screwed upon the top of a Mason jar 23 with the usual gasket 24 interposed between the sealing flange 21 of the lid and the retaining flange 25 of the jar. The tool 10 is then placed over the lid and occupies a position such as shown in Fig. 3. By grasping the knurled portion 13 of the tool, the operator rotates the same and the tapered portion 19 of the lug 18 frictionally engages the edge of the sealing flange 21. At the same time the bevelled edge 15 rides upon the upper surface of the sealing flange 21.

50 55 As the operator rotates the tool, he exerts a downward pressure thereon, forcing the bevelled edge 15 downwardly upon the sealing flange to aid in straightening the same, and causing the tapered portion 19 to wedgably force the edge of the sealing flange downwardly and inwardly and crimp the same

60 into the gasket 24 to effect a perfect seal therewith.

65 70 If it is desired to use jar lids having sealing flanges which are very badly bent or distorted, the tool may be employed in the manner shown in Fig. 5 to first reshape and straighten the sealing flange.

75 80 A split ring or forming die 26 is preferably formed of wire, as shown in Fig. 4, and first positioned around the neck of a jar 23 above its retaining flange 25 and at the base of the threads 27 on the neck of the jar, thus occupying substantially the position to be occupied by the usual gasket. The lid 20' is then screwed on the jar until the ring 26 fits tightly under the lower edge of the sealing flange 21 of the lid. The tool is then placed over the lid, and upon rotating the tool, the lug 18 forces the sealing flange 21' inwardly against the ring 26 to reshape and straighten the flange around its entire periphery. The lid 20' and ring 26 may be then removed from the jar, the gasket positioned thereon, and the lid screwed down onto the gasket; when by rotatively applying the tool to the lid in the manner previously described and illustrated in Fig. 3, the sealing flange is crimped into the gasket to form a perfect seal therewith around the entire periphery of the lid.

85 90 95 It has been found that by using the improved sealing tool, the majority of jar lids may be used over and over again with very satisfactory results, and that even though a new lid is somewhat bent upon being first applied, the tool will straighten the sealing flange and crimp the same into substantially perfect sealing engagement with the gasket.

100 105 By using the split ring as one forming die and the improved tool as the other, it has been found that old lids, which are warped and distorted so as to ordinarily render them unsatisfactory for further use, may be reshaped and then used over again to effect a perfect seal with the gasket.

110 I claim:

115 1 A rotatable cup-shaped tool for straightening and sealing a jar lid having an outwardly flared sealing flange, said tool having a wall adapted to fit around the lid, the lower edge of said wall being adapted to ride upon the top of the sealing flange of the lid, and the wall having an inwardly tapered depending lug formed therein for engaging over the edge of the sealing flange.

120 125 2 A rotatable cup-shaped tool for straightening and sealing jar lids having an outwardly flared sealing flange, said tool having a wall adapted to fit around the lid, and the wall having an inwardly tapered depending lug formed therein for wedgably engaging over the edge of the sealing flange.

130 3 A tool for straightening the sealing flanges of jar covers and simultaneously sealing the same against the gasket, said tool

including an annular wall fitting around the lid and having a ridge on its inner surface, the lower portion of said ridge being tapered to frictionally engage over the outer edge of the sealing flange to crimp the same downwardly inward into the gasket, and the lower edge of said wall being adapted to ride upon the top of the sealing flange to straighten the same.

4. A tool for sealing jar lids having a sealing flange for engaging a gasket, said tool including an annular wall adapted to fit around the lid and having a ridge on its inner surface, and the lower portion of said ridge being tapered to wedgably engage over the outer edge of the sealing flange for crimping the same downwardly inward into the gasket.

In testimony that I claim the above, I have hereunto subscribed my name.

JACOB Z. HUMBERT.
